No. 881,129.

PATENTED MAR. 10, 1908.

W. R. JOHNSTON.
FIRE EXTINGUISHING ENGINE.

APPLICATION FILED JULY 3, 1906.

UNITED STATES PATENT OFFICE.

WALTER R. JOHNSTON, OF NEW YORK, N. Y., ASSIGNOR TO THE WALTER R. JOHNSTON MANUFACTURING COMPANY, OF NEW YORK, N. Y., A CORPORATION OF NEW YORK.

FIRE-EXTINGUISHING ENGINE.

No. 881,129.

Specification of Letters Patent. Patented March 10, 1908.

Application filed July 3, 1906. Serial No. 324,557.

To all whom it may concern:

Be it known that I, WALTER R. JOHNSTON, a citizen of the United States, and residing at New York, in the county of New York and State of New York, have invented certain new and useful Improvements in Fire-Extinguishing Engines, of which the following is a specification, such as will enable those skilled in the art to which it appertains to make and use the same.

This invention relates to engines for use in extinguishing fires, and the object thereof is to provide an improved portable engine of this class which is designed to contain a suitable chemical compound for use in extinguishing fires and which may be used in a variety of ways by means of different elements contained in and forming a part of the engine.

My improved engine involves a bucket of novel construction and provided with a cover having at one edge thereof and flush with one side of the inner wall of the bucket an opening having a hinged or movable cap and means for sealing the same, said bucket being also designed to contain a chemical compound employed, and being provided with a pump whereby said compound may be thrown a considerable distance, and said bucket being also provided with a number of supplemental elements which are placed therein and which may be separately used for the purpose of extinguishing fires, and which are normally filled with the chemical compound and ready for use at all times, and which may be removed from the bucket whenever necessary through the opening in the cover thereof.

The invention is fully disclosed in the following specification, of which the accompanying drawing forms a part, in which the separate parts of my improvement are designated by suitable reference characters in each of the views, and in which:

Figure 1 is a plan view of my improved fire extinguishing engine or device; Fig. 2 a side view thereof; Fig. 3 a sectional plan view showing the cover removed and showing the supplemental fire extinguishing elements placed therein; Fig. 4 a vertical section on the line 4-4 of Fig. 1 and showing the cap of the opening in the top of the bucket raised; Fig. 5 a side and sectional view of coöperating parts of the pump operating devices; Fig. 6 a sectional side view

of a valve device which forms a part of the pump mechanism and showing also a side view of a locking key by which the valve is operated, said key being connected with the piston rod of the pump mechanism when in use; and, Fig. 7 a view similar to Fig. 4 but showing a modification thereof.

In the practice of my invention I provide a bucket *a* having a stationary cover *a*² and in one side of which is an opening *a*³ shown in full lines in Fig. 4 and in dotted lines in Fig. 1, and said opening is provided with a hinged cap *b*, and around the opening *a*³ which is irregular in form as shown in Fig. 1, are collars or flanges *a*⁴, and the cap *b* is provided with corresponding collars or flanges *b*² which fit in the grooves formed by the collars or flanges *a*⁴, and said grooves formed by the collars or flanges *a*⁴, in practice, are filled with a composition of infusorial earth and vaseline so as to form a seal for the cap *b*. The side of the bucket adjacent to the opening *a*³ in the cover thereof is so formed that the inner wall of the bucket is flush with the outer edge of said opening, and said outer edge of said opening is circular in form or corresponds in shape with the said side of the bucket at the top thereof in order to facilitate the discharge of a part of the contents of the bucket in the use of the apparatus as hereinafter described. The stationary cover *a*² of the bucket is also provided with a circular opening *a*⁵ closed by a cap *c*, said cap being held in place by screws *c*², and around the opening *a*⁵ are annular grooves *a*⁶ formed by corresponding collars or flanges, and the cap *c* is provided with corresponding annular flanges *c*³ which fit in said grooves, and in practice, the said grooves *a*⁶ are filled with a composition of infusorial earth and vaseline to form a seal around the opening *a*⁵.

The cap *c* is provided with a depending tubular member *c*⁴ in which is secured a pump cylinder *a* in which is placed a valve piston *d* provided with a rod *d*² which passes upwardly through the cap *c* and around the opening in the cap *c* through which the rod *d*² passes is a gland collar *e* in which is secured a gland *e*², and the collar *e* and the gland *e*² form a stuffing box for the rod *d*² on the outer sides of which are inclined ribs *e*¹ formed on the collar *e*, and one of which is shown in full lines in Fig. 5 and both of which is shown in section in Fig. 4. The collar *e* is also pro-

vided with a port or passage e^3 which connects with a tube e^5 which extends through one side of the tubular member c^4 and communicates with the interior of the bucket or receiver a at the top thereof so as to facilitate the admission of air to the bucket or receiver and facilitates the operation of the pump as hereinafter described.

The rod d^2 of the piston d^2 is provided with 10 a cap f on the inner side of which are inclined ribs r^2 adapted to engage the ribs e^4 of the collar e , and said cap is also provided on one side of the outer side thereof with parallel ribs f^3 , shown in full lines in Figs. 1 and 6 15 and in section in Fig. 4. The piston d^2 is provided with ports or passages d^4 and placed on said piston is a flexible flap valve d^5 , and said ports or passages d^4 are opened when the piston d^2 is moved downwardly and 20 closed by the valve d^5 when the piston d^2 is moved upwardly.

In the bottom portion of the pump cylinder d is secured a foot valve g having ports or passages g^2 , and placed over the same is a 25 flap valve g^3 which operates in the same manner as the valve d^5 , and around the bottom of the pump cylinder d are lateral ports or passages g^4 preferably inclosed by a wire-gauze screen or similar guard g^5 .

30 The upper end or top of the piston d^2 is provided above the cap f with a handle d^6 and said cap is rigidly secured to said rod and moved therewith, and said rod and cap f may also be rotated in which operation the piston 35 d^2 is also rotated, and when the engine is not in use the piston d^2 is forced downwardly into its lowermost position in which operation the cap f incloses the collar e , and said rod and cap are then turned so as to lock the 40 cap f on said collar by means of the above referred to locking devices e^4 and f^2 , and in this position of the parts the port or passage e^3 in the collar e is closed, the object of the port or passage e^3 being to admit air to the 45 bucket or receiver when the pump or engine is in use, and said port or passage being sealed by the cap f when the engine is not in use.

On one side of the cap c is a raised stud h 50 having a horizontal passage h^2 in which is placed a threaded tapered valve plug i , and the stud h is provided with a port or passage h^3 and the tapered valve plug i with a horizontal port or passage i^2 adapted to communicate therewith, and said valve plug is 55 also provided with a collar i^3 having a pin i^4 which normally fits in the groove formed by the ribs f^3 on the outer side of the cap f , and in the operation of securing said cap to the collar e as hereinbefore described, the valve plug i is turned so as to close the port or passage h^3 , and in detaching said cap f from the collar e and raising the piston d^2 the 60 said valve plug is turned so as to open said port or passage.

The threaded portion of the tapered valve plug i fits into a smooth tapered valve casing formed by the stud h and the screw threads on the valve plug i are filled with a compound of infusorial earth and vaseline for the purpose of more thoroughly sealing this joint and prevent the escape of gas from the bucket at this point, or the admission of air thereto, and although I have specified the use of infusorial earth and vaseline as a sealing medium, my invention is not limited thereto and any suitable material may be employed. The valve plug i is also provided at one end with a coupling collar i^5 with which in practice is connected a bent connection j to which is attached a flexible tube k through which, in practice, the contents of the bucket may be forced to a considerable distance, and said tube in practice, is provided with a discharge nozzle, not shown, which may be manipulated in the manner of other devices of this class. Within the bucket a is also placed and normally kept a plurality of supplemental devices or elements which may be used for the purpose of extinguishing fires in a room, compartment, or building where said fires can be conveniently got at. One of these supplemental elements or fire extinguishers consists of a syringe device m which may be inserted into the 95 bucket through the opening a^3 and removed therefrom whenever desired, and said syringe device is made in the manner of other devices of this class such as the "Little Giant" for which Letters Patent of the United States 100 were granted to me on the 28th day of April, 1896, No. 558,959, or in the manner of a similar device shown and described in an application for Letters Patent of the United States filed by me December 7, 1905, Serial No. 290,706; and another of said elements consists of a cup n provided with a handle n^2 and in which is inserted a supplemental cup n^3 in which is inserted a tubular cup n^4 provided with a perforated and removable 110 cover n^5 .

In practice all the supplemental fire extinguishing devices m , n , n^3 and n^4 are normally filled ready for use at all times, and either or all of them may be removed from the bucket for use whenever desired. The operation of the syringe device m will be similar to that of all other devices of this class, while by means of the cups n and n^3 quantities of the fire extinguishing composition may be thrown by hand on a fire, and whenever it is not desired to discharge large quantities of the fire extinguishing compound at a single operation the tubular cup n having a perforated cover n^5 may be used, and by means of this device small quantities of the compound may be discharged on an incipient fire located at any point where it can be got at.

By means of the construction hereinbefore 130

described, I provide an engine for extinguishing fires capable of a large variety of uses and, one which may be conveniently carried about from point to point and by means of which a fire extinguishing liquid or compound may be thrown by means of a pump to a considerable distance, and when it is not desired to use the pump or when the fire is located in a small space, room or compartment and may be conveniently got at, any of the supplemental devices contained in the bucket may be used. The permanent cover of the bucket is also provided with an opening closed by a threaded cap *o* or in any desired way, the object of said opening being to provide means for testing the contents of the bucket without breaking the seal formed by the caps *d* and *e*, and the opening which is closed by the cap *o* may also be sealed if desired in any practical manner.

The chemical compound used in my fire extinguishing engine is the same as that used in what is known as the "Little Giant" fire extinguisher, hereinbefore referred to, and this compound is such that only a small quantity need be used, a small amount thereof being sufficient to put out any ordinary fire at the start, said compound expanding into a gas of many times the volume of the compound when thrown into the fire, which gas extinguishes the fire. The chemical compound which I employ will not injure the hands of an operator, or garments, or any textile material on which it may be thrown, and if in case a fire has gained considerable headway in a room or other compartment, the movable cap *b* may be opened or raised as shown in Fig. 4 and the supplemental fire extinguishers within the bucket may be removed and the contents of the bucket, or a part thereof, may be thrown bodily into the fire through the opening *a*³, this operation being performed by grasping the bail *k*² in one hand and the bottom edge of the bucket at one side thereof in the other hand, and in order to facilitate the operation of the pump which forms the main part of my improved fire engine I place beneath the bottom of the bucket a slide *k*³ having a handle member *k*⁴, and said slide may be drawn out from beneath the bottom of the bucket, and in practice one foot is placed thereon so as to hold the bucket down in the operation of using the pump, and if desired the bottom of the bucket may be provided at the two opposite sides with a similar device for a similar purpose, or any suitable means may be provided on which the feet may be placed to hold the bucket down in the operation of the pump.

It will be understood that the pumping part of the engine may be used whenever necessary without breaking the seal formed by the cap *b* or without opening said cap, and it will also be understood that by open-

ing said cap any part of the contents of the bucket may be discharged through the opening *a*³ in the manner above described, and the supplemental fire extinguishing devices placed in the bucket may be removed at this time and separately used if desired, but it will be apparent that as far as the pumping part of my improved engine is concerned, the said engine or device may be used independently of the supplemental fire extinguishing devices which are placed in the bucket, and my invention is not limited to the use of said devices.

In Fig. 7 I have shown a modification in which the bucket is provided with a permanent cover having a central opening around which is a downwardly or inwardly directed annular flange or rim member *p* having a depending central tube member *p*² with which the pump cylinder *d* is connected, and the opening in the cover of the bucket is closed by the cap *c* the same, or substantially the same, as shown in Figs. 1 and 4, and it will be understood that with this construction all the parts of the pump device or apparatus shown in Figs. 1 and 4 are employed, the object of Fig. 7 of the drawing being to show a modification of the bucket in which the supplemental fire extinguishing devices are not employed and the cover of the bucket not provided with an opening *a*³. The apparatus shown in Fig. 7 being intended to illustrate a device in which only the pump is employed.

By means of the method of constructing my improved fire engine as shown in Figs. 1 to 4 inclusive, it will be observed that the pump part thereof may be entirely detached from the bucket for repair or other purposes by simply removing the cap *c*, and this may also be made true of the construction shown in Fig. 7.

By means of the construction shown and described, it will be apparent that the engine or apparatus, or the pump feature thereof, may be continually operated and new material may be poured into the bucket without stopping the operation of the pump, and after the composition used in the bucket or receiver is exhausted, if no more is convenient, water may be poured into the bucket or receiver and forced through the pipe *k* for the purpose of extinguishing the fire. It will also be apparent that while the engine or apparatus herein shown and described is designed to be operated by hand the same may be made so that the pump may be operated by power if desired. It will also be observed that in Fig. 4 of the drawing the handle *d*⁶ by which the pump is operated is formed integrally with the piston rod *d*³, and the cap *f* formed separately and secured to said rod, but in the construction shown in Fig. 7 the handle *d*⁶ is formed integrally with the cap *f*, and this construction is also shown

in Figs. 5 and 6, but it will be understood that either the construction shown in Fig. 4 or that shown in Fig. 7, in this respect, may be employed.

5 The bucket which forms the main and enclosing part of my improved fire engine may be provided with straps p^4 as shown in Fig. 7 by which it may be carried from place to place, or said bucket may be provided with 10 both a bail k^2 and strap p^4 , and various changes in and modifications of the construction described may be made without departing from the spirit of my invention or sacrificing its advantages.

15 Having fully described my invention, what I claim as new and desire to secure by Letters Patent, is:—

1. In a fire extinguishing engine of the class described, a receiver provided with a 20 cover, said cover being provided with an opening closed by a cap beneath which is the cylinder of the pump which passes downwardly into said receiver, said cylinder being provided with a valved piston having a rod 25 which passes outwardly through a stuffing box connected with said cap and is provided at its end with a handle, said rod and said stuffing box being provided with means whereby the turning of said rod by means of 30 the handle thereof will lock the piston in its innermost position and the rod to said cap, and said cap being provided with a valved coupling in connection with said cylinder, and means for connecting a flexible tube 35 therewith, and the cover of the receiver being also provided at one side with an opening and a sealing cap for said opening.

2. In a fire extinguishing engine of the class described, a receiver provided with a 40 cover, said cover being provided with an opening closed by a cap beneath which is the cylinder of the pump which passes downwardly into said receiver, said cylinder being provided with a valved piston having a rod 45 which passes outwardly through a stuffing box connected with said cap and is provided at its end with a handle, said rod and said stuffing box being provided with means whereby the turning of said rod by means 50 of the handle thereof will lock the piston in its innermost position and the rod to said cap, and said cap being provided with a valved coupling in connection with said cylinder, and means for connecting a flexible tube 55 therewith, and the cover of the receiver being also provided at one side with an opening and a sealing cap for said opening, said sealing cap being hinged between the opening and the pump cylinder.

60 3. In a fire extinguishing engine of the class described, a receiver provided with a permanent cover, said cover being provided with an opening closed by a cap beneath which is a pump cylinder which extends 65 downwardly into said receiver, said cylinder

being provided with a valved piston having a rod which passes outwardly through a stuffing box connected with said cap and is provided at its end with a handle, said rod and said stuffing box being provided with means whereby the turning of said rod by means of the handle thereof will lock the piston in its innermost position and the rod to said cap, and said cap being provided with a valved coupling in connection with said cylinder, and means for connecting a flexible tube therewith, the cover of the receiver being also provided at one side with an opening and a sealing cap therefor, and said receiver being also provided with supplemental fire extinguishing devices which are placed therein and removed therefrom through said opening.

4. In a fire extinguishing engine of the class described, a bucket or receiver provided with a permanent cover having at one side edge an opening closed by a movable sealing cap, said cover being also provided with another opening closed by a detachable sealing cap beneath which is a pump cylinder which extends downwardly into said bucket or receiver, and a piston mounted in said cylinder and provided with a rod which passes outwardly through the detachable sealing cap, said detachable sealing cap being also provided with a valved coupling in communication with said cylinder, and means for connecting a flexible tube with said valved coupling.

5. In a fire extinguishing engine of the class described, a bucket or receiver provided with a permanent cover having at one side edge an opening closed by a movable sealing cap, said cover being also provided with another opening closed by a detachable sealing cap beneath which is a pump cylinder which extends downwardly into said bucket or receiver, and a piston mounted in said cylinder and provided with a rod which passes outwardly through the detachable sealing cap, said detachable sealing cap being also provided with a valved coupling in communication with said cylinder, and means for connecting a flexible tube with said valved coupling, said bucket or receiver being also provided with supplemental fire extinguishing devices which are placed therein and removed therefrom through the first named opening in the cover.

6. In a fire extinguishing engine of the class described, a bucket or receiver provided with a permanent cover having at one side edge an opening closed by a movable sealing cap, said cover being also provided with another opening closed by a detachable sealing cap beneath which is a pump cylinder which extends downwardly into the bucket or receiver, a piston mounted in said cylinder and provided with a rod which passes outwardly through the detachable sealing cap,

5 said detachable sealing cap being also provided with a valved coupling in communication with said cylinder and provided with a valve, and means for connecting a flexible tube with said valved coupling, the cover of said bucket or receiver being also provided with a testing opening.

10 7. In a fire extinguishing engine of the class described, a receiver provided with a permanent cover, said cover being provided in one side thereof and flush with said side with an opening closed by a movable cap, the opposite side of the cover being provided with a pump the cylinder of which extends 15 downwardly into the receiver, and the piston rod of which extends outwardly through the top of the receiver, and supplemental fire-extinguishing devices adapted to be inserted into the receiver and removed therefrom 20 through the opening in the cover and designed for use in throwing a fire extinguishing liquid.

25 8. In a fire extinguishing engine or apparatus of the class described, a receiver provided with a permanent cover, said cover being provided with an opening closed by a cap beneath which is a pump cylinder which extends downwardly into said receiver, said cylinder being provided with a valved piston 30 having a rod which passes outwardly through a stuffing box connected with said cap and is provided at its end with a handle, said rod and said stuffing box being provided with means whereby the turning of said rod by 35 means of the handle thereof will lock the pis-

ton in its innermost position and the rod to said cap, and said cap being provided with a valved coupling in connection with said cylinder, the outer casing of the stuffing box being also provided with a port or passage 40 which communicates with the interior of the receiver and which is closed when the piston is locked in its innermost position.

45 9. In a fire extinguishing engine of the class described, a receiver provided with a permanent cover, said cover being provided with an opening closed by a cap beneath which is a pump cylinder which extends outwardly into said receiver, said receiver being provided with a valved piston having a rod 50 which passes outwardly through a stuffing box connected with said cap and is provided at its end with a handle, said rod and said stuffing box being provided with means whereby the turning of said rod by means of 55 the handle thereof will lock the piston in its innermost position and the rod to said cap, and said cap being provided with a valved coupling in connection with said cylinder, and means whereby the turning of said rod 60 will open or close said valve according to the direction in which said rod is turned.

65 In testimony that I claim the foregoing as my invention I have signed my name in presence of the subscribing witnesses this 2nd day of July 1906.

WALTER R. JOHNSTON.
